DESPATCHING SYSTEM FOR BANKS OF
ELEVATORS AND THE LIKEHenry Léopold Roger Roche, Paris, France, as-
signor to Société Anonyme Etablissements
Edeux-Samain, Paris, FranceApplication June 3, 1932, Serial No. 615,207
In France June 16, 1931

7 Claims. (Cl. 187—29)

The present invention relates to an electrical controlling device for calling or despatching passenger elevators or freight elevators, particularly adapted for installations comprising several elevators and the latter being of the known type wherein at each floor is located a single call button, which is common to all the elevators. A selector and a registering apparatus are connected in a known manner, with the relays and contacts 5 for the control of the elevators.

My invention is particularly applicable to an elevator despatching system wherein a single button on each floor controls a plurality of elevators and records the floor signals as transmitted and 15 sends the first available car to the calling floor. My invention will be better understood from the following specification and accompanying drawings wherein:

Figure 1 shows the novel features of the system, 20 of my invention including the control relays and their wiring and,

Figure 2 shows the operating system of a bank of elevators to which my despatching system has been applied.

In known elevator controlling means of this 25 type, the principal aim is to utilize in the most advantageous way possible, each unengaged car of a bank of elevators.

A somewhat satisfactory result may be had with 30 known installations by using cars of a relatively large capacity, for instance, sufficient to accommodate ten or more persons, and providing control means adapted to stop the elevator car at an intermediate floor during its travel, so that the 35 car is brought to a stop at the floor where the call is made thereby allowing the passenger to board the elevator before the same continues the journey to its original destination.

Such elevator installations aim to provide for 40 the transportation of a considerable number of passengers on one trip, which is, for example, the case in installations of large stores or buildings having a relatively large number of stories. In practice, such known installations present numerous inconveniences, if the capacity of the cars is reduced to five or six persons.

During particularly rush hours, the upper and lower floors are alone practically served, because 50 the cars may be filled at the start and consequently unable to accommodate passengers at intermediate floors.

Therefore, the intermediate floors can never be 55 assured of satisfactory service since the cars respond to calls according to a set order and the

calls are not responded to in accordance to their priority.

Hence, in the known installations, an intermediary call, that is, a call originating at one of the intermediate floors, can be responded to during 5 the travel of the car, and each passenger must pay especial attention when the car stops at a certain floor, and that because of the possibility that the car is responding to calls from intermediate floors. Therefore, the passenger cannot, 10 under these conditions be certain that the car will first stop at the floor desired.

Contrary to the known elevator controls, the present invention does not especially contemplate the solution of the problem of complete individual utilization of calling means for each car taken separately. In fact, the elevator installation comprising the novel control of the cars is distinguished from known installations above referred to by the following peculiarities: 20

1. The capacity of the cars is relatively small, for example, two to four persons, or in the case of a factory freight elevator, the loads may be divided in three or four parts.

2. When a car is first placed in motion by actuation of a call button, in responding to this call, the car completely answers the call and reaches the desired floor. The calls originating at the intermediate floors have no effect on this car.

3. When the cars are all occupied, the calls are 30 first registered and responded to just as the cars become available and in a determined consecutive order. A call from a floor button will be responded to only after the control order signals from the cars are completely executed. 35

This system is advantageously used with the type of elevator car provided with a depressible floor platform upon which the passenger stands and which actuates a control circuit.

The users, therefore, by means of the new system, are served individually so to speak. Consequently, the new elevator installation is particularly devised for buildings having a relatively small number of stories and for relatively short car travel where it is not aimed to obtain a determined amount of performance from each car per minute, but where due to the complete automatic feature of the installation, the passengers may run the elevators themselves, which eliminates the necessity of an attendant. 50

The control elements of the present system are the buttons arranged in the cars, which in itself may be a known arrangement, the buttons in each car being equal in number to that of the floors. According to the present system, there 55

is provided but one call button at each floor. A selector, which may be of any suitable known type, combined with registering means, forms a part of the control system of the elevators, and 5 to realize the purpose of this system, the selector is connected to a set of relays suitably disposed.

The arrangement of the selector contact points is, in accordance with the present invention, preferably circular. However, it will be understood 10 that the selector contact points may be arranged differently if a particular installation so requires. The contact brush or finger disposed radially of the circularly arranged selector contact points, revolves and passes successively over 15 said points, which assures the successive response to all registered calls. The selector includes a contact point for each story for each elevator, and the contact points corresponding to the same story are arranged side by side.

20 In the operation of the system according to this invention, two cases may present themselves:

1. The presence of available cars.
2. All cars are occupied.

In the first case, when a call button of a certain floor is pressed, each one of the group of contact points of the selector which correspond to this floor and which are equal in number to the number of the elevators, is energized if the elevator corresponding to that contact point is available; the brush rotates and passes from contact point to contact point until it reaches the first live contact point. The engagement of the brush with the contact point results in setting in motion the elevator corresponding to said contact 35 point. This elevator is then directed towards the floor from which the call was sent. As soon as it starts moving, the contact points corresponding to this floor are deenergized. It is to be noted that the selector brush stops as soon as it reaches 40 the first contact point which is live and resumes its movement only under the influence of another call which has been registered and only if there are available cars.

If all the cars are occupied, the calls coming 45 from the various floors are registered, that is, they prepare the circuits for the energizing of the selector contact points corresponding to said floors, and for the operation of the selector, provided no car is then on its way to that floor at the 50 time the button is pressed. Relays provided with holding contacts are employed. As soon as a car becomes available (due to the release of the depressible platform in the car, the closing of the doors, and the elevator stopping) the selector brush starts moving and passes from contact point to contact point until it reaches the first energized contact point. The available car corresponding to this contact point is then directed 55 towards the floor corresponding to the call made and this deenergizes the registering relay corresponding to that floor which is actuated by the floor button. The selector brush then stops due to the fact that there are no more available cars. If several calls are registered, as soon as this same 60 car or another becomes available, the selector brush starts moving and stops anew upon the first live contact point and so on until all calls have been satisfied. It is to be noted that calls transmitted during the travel of the car have no 65 influence on the latter but are simply registered until one of the cars becomes available. The controls from the buttons within the cars have priority over the calls originating from the floors.

70 It is also to be noted that one of the floors, 75 which is generally the lobby, will require more

service than the others. It is therefore important that at least one elevator be always available at this lower floor. The present system satisfies this latter condition, in that the system operates in such a manner that if no one of the cars is 5 at the lobby, a call for this floor is automatically registered by contacts mounted in the shaft and actuated by the car according to whether the car is or is not in its terminal position.

As soon as a call, automatic or button, from 10 the lobby floor is executed and the car arrives at the lobby floor, the car is held there and does not respond to calls from the upper stories so long as another car from the bank of elevators remains available. The car at the main floor becomes 15 free to respond to calls only if the other cars are occupied. A call from an upper floor will be responded to by a car left available at the upper floors in preference to a car stationed at the main floor or lobby.

20 For a better understanding of the invention and to make the details likewise apparent, the following description with reference to the accompanying drawings shows, by way of example, an embodiment of the invention.

25 The present system is composed of two parts. Figure 1 illustrates the novel features of the installation, and Figure 2 comprises known elements which are combined with the features represented on Figure 1. The same characters of 30 reference applied to the conductors on both figures, will permit to follow the circuits from one figure to the other.

In the example shown, it is supposed that there 35 are four stories to be served and three elevators.

On the drawings, the relays have been designated by numerals and their contacts by small letters. Moreover, to facilitate reading of the drawings, the elements particularly pertaining to the elevator A have been designated by numerals 40 terminating by 1, 4, and 7; the elements particularly pertaining to the elevator B have been designated by numerals terminating by 2, 5, and 8; the elements particularly pertaining to the elevator C have been designated by numerals 45 terminating by 3, 6, and 9; and, the elements common to all elevators A, B and C have been designated by numerals terminating by cipher.

As will appear from Figure 1, the selector 200 is represented for clarity in two places. The 50 ratchet wheel and the selector contact brush which have been shown in two places on the drawings represent the same arrangement. At the left, is seen the arrangement of the selector contact points and at the right the control mechanism of the selector brush.

For convenience in reference, certain of the more important groups of reference characters are here tabulated:

7, 8, 9 terminal shaft switches.

14, 15, 16 terminal relays (respectively for cars A, B, C).

21, 22, 23, groups of hatchway door switches, one group for each car.

24, 25, 26 car door switches, one for each car.

30, 40, 50, 60, floor button actuated registering relays (corresponding respectively to floors I, II, III, IV).

31, 32, 33 car platform switches (respectively for cars A, B, C).

44, 45, 46 car door operated relays (also controlled by floor hatchway doors) (respectively for cars A, B, C).

47, 48, 49 intermediate relays (controlled respectively by relays 51, 54, 44, by 52, 55, 45, and 75

by 53, 56, 46, for preparation and preliminary control of the selector actuator).

51, 52, 53 car platform actuated relays (respectively of cars A, B, C).

5 54, 55, 56 moving car actuated reversing relays with delayed release (actuated when car is in motion) (respectively for cars A, B, C).

70, 80, 90, 100 floor push buttons (one for each floor).

10 87, 88, 89; 91, 92, 93; 94, 95, 96; 97, 98, 99 despatching relays, one for each floor for each car, and controlled by the floor hatchway door:

101, 104, 107, 111 push buttons on panel in car A.

102, 105, 108, 112 push buttons on panel in car B.

15 103, 106, 109, 113 push buttons on panel in car C.

118, 121, 122, 123, 161, 162, 163, brush on frictional contactors.

124, 125, 126, 127, 128, 129, the usual elevator relays controlling motor and brake circuits.

20 131, 132, 133, 157, 158, 159, rotating contactor disks.

137, 138, 139 brake magnets.

141, 142, 143 elevator motors.

144, 145, 146 elevator brake drums.

25 160 selector actuating relay.

170, 180 step relays controlling the selector.

200 selector.

210 selector armature.

In accordance with the invention, a call button

30 70, 80, 90, 100, is placed at each floor, but for the sake of clarity, these buttons have not been represented at their normal position. They have been shown adjacent the floor button actuated

registering relays 30, 40, 50, and 60 which are controlled by these buttons. The action of these

35 buttons is to place in contact one of the supply terminals P¹ of the source of electric current with the respective floor button relays 30, 40, 50, 60 which are in turn connected to another supply

40 terminal P² of the source of current by means of contacts 87b, 88b, 89b, contacts 91b, 92b, 93b, contacts 94b, 95b, 96b, and contacts 97b, 98b, 99b.

When the floor button relays 30, 40, 50, 60 are energized, they act to respectively close their

45 contacts a, b, c, d, e.

The closing of contacts 30e, 40e, 50e, 60e results in the holding respectively of the corresponding relays 30, 40, 50, 60 by connecting them directly to the terminal P¹ of the source of current without

50 passing through the button 70, 80, 90, 100.

The closing of contacts 30 a, b, c, contacts 40 a, b, c, contacts 50 a, b, c, and contacts 60 a, b, c, results in respectively connecting one of the supply terminals of the source of electric current with

55 a series of contact points 71, 72, 73, 74 to 83, by means of the respective contacts 51a, 54a, 44a,

52a, 55a, 45a, 53a, 56a, 46a and of the groups of two circuits placed in parallel and certain of which comprise the respective contacts 48b, 49b,

60 contacts 49c, 47b, contacts 48c, 47c and the others comprising the respective contacts 14c, 15c, 16c.

Adjacent contact points 71, 72, 73 to 83 there are placed other corresponding contact points 57,

65 58, 59, 61 to 69 respectively which are connected to the groups of despatching relays 87, 88, 89, relays 91, 92, 93, relays 94, 95, 96, and relays 97, 98, 99. There are as many of these despatching relays for each car as there are floors, and they

70 are controlled by the floor hatchway doors, as one of their controls.

These relays control the corresponding elevator (elevator A, elevator B, elevator C) to cause it to move to the corresponding floor I, II, III, IV.

75 These relays are energized either by the circuits

hereinbefore described, or by action of the buttons 101, 104, 107, 111, buttons 102, 105, 108, 112, and buttons 103, 106, 109, 113, mounted on the panel in the car, and which, as stated, have not been shown at their normal location. The energization by these buttons takes place by means of the circuits: supply terminal P¹, 44c, 54c; circuit P¹, 45c, 55c; circuit P¹, 46c, 56c. The closing of contacts 87a, 91a, 94a, 97a, contacts 88a, 92a, 95a, 98a, and contacts 89a, 93a, 96a, 99a, 10 results in the respective holding of the corresponding despatching relays in connecting them by means of circuit P¹, 44c, circuit P¹, 45c, and circuit P¹, 46c, to the supply terminal P¹, without passing through the buttons 101 to 113, or 15 the special circuits of the selector contact points. According to the invention, the energization of despatching relays 87, 91, 94 to 99 acts moreover to open their contacts b, hereinbefore mentioned.

Said contact points 71, 72, 73 to 83 and 57, 58, 20 59 to 69 may be respectively and successively placed in contact (71 with 57, 72 with 58, etc.) by suitable means for example by the arrangement known as the "step by step selector". This apparatus is circular and its mechanism is schematically illustrated at 200. Its electric actuating circuit comprises, as shown, the contacts 47a, 48a, 49a, and the contacts 30d, 40d, 50d, 60d.

Corresponding to the position of the car at the main floor or lobby are located three switch contacts 7, 8, 9 corresponding to the elevators A, B, C. These contacts close the respective circuits of terminal relays 14, 15, 16 each of these circuits being completely closed only if the respective contacts 15a, 16a, 16b, 14a, 15b, 14b are likewise closed. These contacts are normally closed, but are opened if their respective terminal relays 14, 15, 16 are energized. It will be readily understood that such an arrangement causes the first elevator to reach the main floor to energize 40 one of the corresponding terminal relays 14, 15 or 16. This energization prevents the subsequent energization of one of the other two terminal relays when a second car reaches the main floor which is supposed to be the floor I upon the 45 drawings.

The energization of a terminal relay 14, 15 or 16 likewise acts to open one of the contacts 14d, 15d, 16d which are connected in series.

The excited terminal relay 14, 15 or 16 likewise acts to open the corresponding contacts 14c, 15c, or 16c. It follows that the arrival of the first elevator car at the main floor acts to open one of the two circuits feeding the current to 55 the selector contact points corresponding to said elevator car.

In accordance with the present invention, the contacts b of relays 51, 54, 44, the relays 52, 55, 45; and the relays 53, 56, 46 respectively close 60 the circuits of relays 47, 48, 49.

The moving car actuated reversing relays 54, 55, 56, and the car platform actuated relays 51, 52, 53 are energized and their contacts b respectively opened if the elevator car under consideration is moving or if the car platform is lowered under the weight of a passenger. The car door operated relays 44, 45, 46 are deenergized and their contacts b opened if a door of the corresponding elevator is open.

70 It is to be noted that the moving car actuated reversing relays 54, 55, 56 are delayed in releasing upon being deenergized so that when an elevator car stops at a floor, a passenger has time to use the car and to thus control the energiza-

tion of the relay or relays 51, 52, 53 before the contacts of relays 54, 55, 56 are again closed.

The signaling devices have been represented upon the drawings only for the third floor to avoid complication of the drawings. The signalling system consists of a suitable number of electric lamps 90b, 94c, 95c, 96c, placed at each floor and respectively actuated by the floor button actuated registering relays 30, 40, 50, 60 and also by the despatching relays 87, 91, 94, 97, the despatching relays 88, 92, 95, 98 and the despatching relays 89, 93, 96, 99. By means of the lighted lamps, it is possible for the prospective passenger to determine at each floor whether a call has been registered or whether a car is moving towards the particular floor and, if so, which elevator car.

The following explanation of the operation of the system will facilitate the understanding of the cooperation of the different circuits of the present system.

Let it be supposed that the three elevators A, B, C, are available and in the positions represented on the drawings. The elevator car A has reached the lowermost floor and has acted by means of the cam 1 placed on the counterweights 4, upon the switch contact 7, thus closing the circuit from terminal P¹, conductor 10, contact 7, conductor 11, terminal relay 14, conductor 17, rest contacts 15a and 16a of terminal relays 15 and 16, supply terminal P², occasioning the energization of terminal relay 14. The rest contacts 14a and 14b are open thus preventing the energization of terminal relays 15 and 16, even if contacts 8 and 9 are closed by the respective action of cams 2 and 3. The elevator car C when reaching the main or terminal floor, closes the contact 9 but for the reason above mentioned, the terminal relay 16 remains unaffected.

The elevators A, B, C are available, that is, for each elevator which is stopped and at rest, the floor hatchway door operated switches, 21 for the elevator A, 22 for the elevator B, 23 for the elevator C, are closed as well as the car door switches 24, 25 and 26, and moreover, the movable platforms 27, 28 and 29 are not depressed and contacts 31, 32, 33 are open.

The following relays are energized:

For the elevator A, the terminal relay 14 as above indicated and the car door relay 44 and the intermediate relay 47; elevator B, car door relay 45 and intermediate relay 48; elevator C, car door relay 46 and intermediate relay 49. That is, for the elevator A, the circuit passing by the circuit terminal P¹, conductor 10, conductor 34, car door switch 24, conductor 37, floor hatchway door operated switches 21, conductor 41, car door relay 44, circuit terminal P², energizes the car door relay 44, and the circuit from terminal P¹, through contacts 51b and 54b, contact 44b, relay 47, circuit terminal P², excites the intermediate relay 47. Analogous circuits energize the relays corresponding to the elevators B and C.

The buttons 70, 80, 90, and 100 are the call buttons for the various floors there being one button per floor. In order to eliminate useless complication of the drawings, these buttons have not been shown at their usual positions. These call buttons cause the energization of their respective floor button actuated relays 30, 40, 50, and 60 which registers the call and, due to their holding contacts 30e, 40e, 50e, and 60e, remain energized as long as the following circuits remain closed. For floor button relay 30: conductor

110, rest contacts 87b, 88b, 89b, supply terminal P²; for relay 40: conductor 120, rest contacts 91b, 92b, 93b, supply terminal P²; for relay 50: conductor 130, rest contacts 94b, 95b, 96b, supply terminal P²; for relay 60: conductor 140, rest contacts 97b, 98b, 99b, supply terminal P². Each of these circuits is opened as soon as one of the three elevators is directed towards the floor corresponding to the floor button registering relay which controls this circuit. The despatching relays 87, 88, 89 and 91 to 99 are in fact, the relays for elevators A, B, and C which correspond to particular floors. For example, the relay 95 is energized when the elevator B is directed towards the third floor, as will be more fully described hereinafter.

It will be appreciated that the contact points 71, 74, 77, 81 of the selector which correspond to the elevator A, can not be energized, since the terminal relay 14 itself is energized and the contact 14c opened, unless the circuit passing through 84, rest contacts 49b, 48b, contact 44a, rest contacts 54a and 51a, supply terminal P¹, is closed. In this case, only the contact points corresponding to certain floors or calls which are registered, will be energized due to contacts 38a, 40a, 50a, and 60a. In order that the contacts 49b, 48b may be closed, it will be necessary that the relays 49 and 48 be deenergized, for which purpose it will be necessary that the elevators B and C be occupied. For example, the elevator B is not available and the relay 48 is deenergized either if the contact 45b is open or if the rest contact 55b is open, (elevator in motion) or if the rest contact 52b is open (with a passenger in the car and the movable platform depressed) as will hereinafter appear.

If the call button 90 of the 3rd floor is pressed, the circuit 130 passing through rest contacts 94b, 95b, 96b being closed, the floor button actuated relay 50 registers the call and remains energized due to its holding contact 50e, even if the floor button 90 is no longer pressed. An auxiliary contact controlled by this relay, but shown on the drawings as 90a only for floor button 90, illuminates an indicating light or signal 90b placed adjacent the call button and indicates thus that the call is registered. The three contacts 50a, 50b, 50c, are closed, and the contact points 78, 79 are energized. The contact point 77 is not energized because the circuit 84 passing through rest contacts 49b, 48b, (intermediate relays 49 and 48 energized, elevators B and C available) and the circuit 84 passing through the rest contact 14c (terminal relay 14 energized) are open. The floor button actuated relay 50 likewise closes its contact 50d. The elevators A, B, and C being available and intermediate relays 47, 48, 49 being energized, the contacts 47a, 48a, 49a arranged in parallel are closed. The circuit passing through circuit terminal P¹, parallel contacts 47a, 48a, 49a, conductor 150, contact 50d, electromagnet 160 of the selector, selector step relay 170, terminal P², is closed. The selector armature 210 is at this moment in the unactuated position shown in Fig. 1 and its end which is opposite to the end which is acted on by the electromagnet is in ratchet engagement with a ratchet wheel of the selector 200. The current is insufficient for the electromagnet 160 to attract its armature, but sufficient for the selector step relay 170 to close its contact 170a. The secondary selector step relay 180 is energized, its armature 180a shunts the winding of 75

- relay 170, and terminal P² is connected directly to selector winding 160 so that armature 210 of selector 200 is actuated and acts on the ratchet wheel. The step relays 170 and 180 release, the 5 armature 210 resumes its rest position and the selector brush advances over a contact point, which process is repeated. The contact point 78 is reached, the circuit passing through 78, 65, despatching relay 95, conductor 115, brush 113, 10 contactor disk 132, contact 122, rest contacts 125c, the actuating winding of lift motor control relay 128, and the terminal P², is closed. The floor despatching relay 95 and the lift motor control relay 128 of the elevator B are energized. 15 The despatching relay 95, due to its holding contact 95a remains energized even if the contact points 78, 65 are disconnected; provided, of course, the safety car door actuated contact 45c remains closed. The despatching relay 95 20 by its auxiliary contact 95c lights the luminous signal 95c at the floor III, indicating thus to the person making the call at that floor, that the elevator B is responding to the call.
- The despatching relay 95 opens its contact 95b 25 thus causing the opening of the circuit passing through the floor button relay 50, conductor 130, contacts 94b, 95b, 96b, and the floor button relay 50 releases. The contact 50d opens and, as it is supposed that the registering floor button actuated relay 50 alone is excited (floor button relays 30, 40, 60 being unactuated), the selector mechanism receives no current and therefore instantly stops, the brush remaining upon the contact points 65, 78. The condenser 190 serves to regulate the speed of the selector. The motor control lift relay 128 closes its contact d which, from terminal P¹ through the conductor 135 energizes the moving car relay 55. The rest contact 55b opens and the relay 48 releases, the elevator B is 40 in use. The electromagnet of the brake for the elevator B is energized due to the closure of contact 128c. The brake drum 145 is released. The terminal 147 of the motor is energized. The other two motor terminals 152 and 155 are likewise 45 energized through the contacts 128b connecting the supply terminal P¹ to 152, and through contact 128a connecting the supply terminal P³ to 155. The operation of the motor causes the elevator car to move by means of cables in the usual manner. The two contactor disks 132 and 158 are 50 displaced proportionally to the car, being actuated by the car by known reduction means. The disks rotate until an instant when the brush contactor 113 assumes a position between the two disks. 55 This causes interruption of the circuit, the despatching relay 95 and the relay 128 release, the brake is actuated, the motor is disconnected and the elevator B stops at the third floor. The delayed action moving car relay 55 releases gradually thus reestablishing its contacts a, b, c, with a certain retarded action permitting the passenger to have time for opening the door. The circuit passing from the supply terminal P¹, through rest contacts 52b, 53b, contact 45b, thus remains 60 open and the relay 48 remains unactuated (the elevator not being available). In fact, if the contact 55b closes, the opening of the door of the elevator B at the third floor has opened the circuit of car door operated relay 45 which releases thus 65 opening contact 45b. The passenger enters the car and consequently depresses the movable car platform 23 of car B. The contact 32 is closed and allows energization of car platform actuated relay 52 which, through its rest contact 52b which 70 opens, keeps the intermediate relay 48 unactuated 75

even though the closure of the doors brings about the energization of car door operated relay 45 and the closing of contact 45b. The elevator B remains "unavailable" for calls made from the floors.

The passenger presses the car button 105 for the second floor, this button, for sake of clarity, has not been shown as in the elevator car, but adjacent the despatching relay 92 corresponding to the second floor and which is controlled by that 10 button. The actuation is made in the manner hereinbefore described, but the circuit coming from the despatching floor relay 92 passes through the friction contact 162, the motor control drop relay 125, to return to the supply terminal P². 15 Upon arriving at the second floor, that is, floor II, the passenger steps out of the car. The relay 52 actuated by the movable car platform releases, and when the doors are closed, the energization of the car door relay 45 closes the contact 45b, 20 which energizes the intermediate relay 48. The elevator B then becomes available.

Coming back to the initial state, if it is now supposed that two calls are simultaneously made and registered by floor button actuated relays 25 59 and 69 (calls from floors III and IV), as hereinbefore mentioned, the brush passing over the contact points 65-78 sends the elevator B to the floor III and deenergizes the floor button actuated relay 50. The floor button actuated relay 60 30 remains energized and maintaining its contact d closed, keeps the selector rotating through the circuit passing by the conductor 159, rest contact 16c, contact 46a, rest contacts 56a and 53a, supply terminal P¹, for the elevator C is supposed to 35 be available. The brush continues its movement until it reaches the contact points 69, 83 and the elevator C answers the second call in the same manner as done by the elevator B. Its corresponding despatching floor relay 99 is energized 40 and the floor button actuated relay 60 returns to the unactuated position stopping the selector. The elevators B and C being in use, the intermediate relays 48 and 49 are released, the rest contacts 48b and 49b close the circuit which 45 shunts the contact 14c which is at the moment opened. In case of a new call, for example at floor II, the contact point 74 is excited and the elevator A, supposedly available, will respond to this call although the terminal relay 14 is energized, because the elevators B and C are not 50 available.

If none of the elevators A, B, C are available, the registering of a call, for example by the floor button actuated relay 30, only has the effect of 55 preparing the energization of contact points 71, 72, and 73 by the closing of contacts 30a, 30b, 30c, and the control of the selector by the contact 30d. The contact point 71 for example will really be energized only by the closing of the circuit passing 60 through the conductor 84, rest contact 14c, contact 44a, rest contacts 54a and 51a, that is if the elevator A becomes available. The selector will be actuated if one of the circuits passing through the conductor 150 and the contact 47a or through 65 the conductor 150 and the contact 48a, or alternatively through the conductor 150 and the contact 49a, is closed, that is if one of the elevators becomes available.

The control of the automatic recall to floor I 70 takes place if the conductor 220, indicated in dotted lines, is provided with suitable shunt connections. The control of registering relay 30 which is normally made by the floor call button, is in this case made not by the call button 70 of 75

the floor I, but by the circuit passing through the conductor 220, the rest contacts 16d, 15d, 14d and the supply terminal P¹. This control, therefore, occurs only if no elevator is stationed at the floor I. If an elevator is at the first floor, one of the contacts 7, 8 or 9 is closed. The corresponding terminal relay 14, 15, or 16 is energized and one of the rest contacts 14d, 15d or 16d is opened, and no automatic order is registered at 5 to send a car to the first floor, this control action will also take place if one of the elevators is traveling in the direction of the floor I when the conductor 110, rest contacts 87b, 88b or 89b is opened and the relay deenergized.

15 It will appear that it is impossible to pass the contact points of a certain floor, for example floor III, without causing the elevator to answer a call made from that floor, if the registering floor button actuated relay 50 corresponding to that floor has been energized by transmitting the call. In fact in order that the selecting contact brush may move, it is necessary that at least one elevator be available, and consequently, there will be in the example chosen at least one of the three 20 contact points 77, 78, 79 which will be excited, and the control will be operated in the manner hereinbefore described.

It will be obvious that it is impossible to answer twice a call from one floor before the selector brush has passed once over all the contact points corresponding to every other floor and consequently, satisfy all the calls registered for said other floors. This is assured because the contact points of all the elevators of the bank corresponding to a single floor are arranged side by side in the successive arrangement of the contact points.

The movement of the brush is made always in the same direction, and consequently it will be evident that if the elevators are all available, it is always the elevator having in the group of contact points corresponding to a floor, the first contact point to be engaged, which will in preference answer the call, unless its elevator is stopped at the floor which is calling, terminal relay 14, or 40 15 or 16 being energized. In practice, since the elevators are rarely stopped together at the same floor, it is possible to evenly distribute the traffic to be handled by the elevators.

Having now particularly described and ascertained the nature of my said invention, and in what manner the same is to be performed, I declare that what I claim is:

1. In an automatic elevator despatching system for a bank comprising a plurality of elevator cars, tractive motors for said cars respectively, a single button on each floor served by said cars, a plurality of groups of despatching relays comprising one group for each floor and each group comprising one relay for each car, said despatching relays being connected for actuating said car motors, a step-by-step electrically actuatable selector comprising a plurality of engageable contact points corresponding respectively to said despatching relays and connected for successively actuating said despatching relays through said contact points respectively, the contact points corresponding to the same floor being positioned adjacent each other, and individual means actuatable by the operation of each of said cars connected for controlling the despatching relays corresponding to said car through said selector according as said car is or is not in use.

2. In an automatic elevator despatching system for a bank comprising a plurality of elevator cars, tractive motors for said cars respectively, a single

button on each floor served by said cars, a plurality of groups of despatching relays comprising one group for each floor and each group comprising one relay for each car, said despatching relays being connected for actuating said car motors, a step-by-step electrically actuatable selector comprising a plurality of engageable contact points corresponding respectively to said despatching relays and connected for successively actuating said despatching relays through said contact points respectively, the contact points corresponding to the same floor being positioned adjacent each other, switch means in each car actuatable by the presence of a passenger therein, a plurality of car platform relays respectively actuatable by said switch means, a plurality of moving car delayed release relays respectively actuatable by the movement of each car, a plurality of floor call registering holding relays respectively actuatable by said buttons, and intermediate relays connected between said other relays for operating said selector when a call from a said floor button is registered on a said floor call relay to actuate the despatching relay of an unoccupied available car at rest corresponding to 5 said calling floor.

3. In an automatic elevator despatching system for a bank comprising a plurality of elevator cars, tractive motors for said cars respectively, a single button on each floor served by said cars, a plurality of groups of despatching relays comprising one group for each floor and each group comprising one relay for each car, said despatching relays being connected for actuating said car motors, a step-by-step electrically actuatable selector comprising a plurality of engageable contact points corresponding respectively to said despatching relays and connected for successively actuating said despatching relays through said contact points respectively, the contact points corresponding to the same floor being positioned adjacent each other, switch means in each car actuatable by the presence of a passenger therein, a plurality of car platform relays respectively actuatable by said switch means, a plurality of moving car delayed release relays respectively actuatable by the movement of each car, a plurality of floor call registering holding relays respectively actuatable by said buttons, and intermediate relays connected between said other relays for operating said selector when a call from a said floor button is registered on a said floor call relay to actuate the despatching relay of an unoccupied available car at rest corresponding to 30 said calling floor, and said floor call register holding relays being adapted for storing unanswerable calls and being connected to said other relays for partially preparing said other relays to complete the response to an unanswerable call so stored as soon as a car becomes at 35 rest and available, and for rendering said preparation ineffective as to a particular floor as soon as a car is despatched to that floor.

4. In an automatic elevator despatching system for a bank comprising a plurality of elevator cars, tractive motors for said cars respectively, a single button on each floor served by said cars, a plurality of groups of despatching relays comprising one group for each floor and each group comprising one relay for each car, said despatching relays being connected for actuating said car motors, a step-by-step electrically actuatable selector comprising a plurality of engageable contact points corresponding respectively to said despatching relays and connected for successively 40

- actuating said despaching relays through said contact points respectively, the contact points corresponding to the same floor being positioned adjacent each other, switch means in each car 5 actuatable by the presence of a passenger therein, a plurality of car platform relays respectively actuatable by said switch means, a plurality of moving car delayed release relays respectively actuatable by the movement of each car, a plurality 10 of floor call registering holding relays respectively actuatable by said buttons, a plurality of terminal switch means respectively actuatable by each of said cars when stopped at a principal floor, a plurality of terminal relays respectively 15 actuatable by said terminal switch means, and intermediate relays connected between said other relays for operating said selector when a call from a said floor button is registered on a said floor call relay to actuate the despaching relay of an unoccupied 20 available car at rest corresponding to said calling floor, and said terminal relays being respectively connected for automatically registering a floor call to said principal floor whenever no car is stopped at said principal floor.
- 25 5. In an automatic elevator despaching system for a bank comprising a plurality of elevator cars, tractive motors for said cars respectively, a single button on each floor served by said cars, a plurality of groups of despaching relays comprising one group for each floor and each group comprising one relay for each car, said despaching relays being connected for actuating said car motors, a step-by-step electrically actuatable selector comprising a plurality of engageable contact points corresponding respectively to said despaching relays and connected for successively actuating said despaching relays through said contact points respectively, the contact points corresponding to the same floor being positioned adjacent each other, individual means actuatable by the operation of each of said cars connected for controlling the despaching relays corresponding to said car through said selector according as said car is or is not in use, and a plurality 20 of individual despaching visual signals at each of said floors corresponding respectively to each of said elevators and actuatable individually respectively by the closing of a corresponding despaching relay to indicate the despaching of the particular responding elevator to the calling floor.
- 30 7. In an automatic elevator despaching system for a bank comprising a plurality of elevator cars, tractive motors for said cars respectively, a single button on each floor served by said cars, a plurality of groups of despaching relays comprising one group for each floor and each group comprising one relay for each car, said despaching relays being connected for actuating said car motors, a step-by-step electrically actuatable selector comprising a plurality of engageable contact points corresponding respectively to said despaching relays and connected for successively actuating said despaching relays through said contact points respectively, the contact points corresponding to the same floor being positioned adjacent each other, switch means in each car 35 actuatable by the presence of a passenger therein, a plurality of car platform relays respectively actuatable by said switch means, a plurality of moving car delayed release relays respectively actuatable by the movement of each car, a plurality of floor call registering holding relays respectively actuatable by said buttons, a plurality of terminal switch means respectively actuatable by each of said cars when stopped at a principal floor, a plurality of terminal relays respectively 40 actuatable by said terminal switch means, and intermediate relays connected between said other relays for operating said selector when a call from a said floor button is registered on a said floor call relay to actuate the despaching relay of an unoccupied available car at rest corresponding to said calling floor, and a plurality of individual despaching visual signals at each of said floors corresponding respectively to each of said elevators and actuatable individually respectively by the closing of a corresponding despaching relay to indicate the despaching of the particular responding elevator 45 to the calling floor.
- 45 6. In an automatic elevator despaching system for a bank comprising a plurality of elevator cars, tractive motors for said cars respectively, a single button on each floor served by said cars, a plurality of groups of despaching relays comprising one group for each floor and each group comprising one relay for each car, said despaching relays being connected for actuating said car motors, a step-by-step electrically actuatable selector comprising a plurality of engageable contact points corresponding respectively to said despaching relays and connected for successively actuating said despaching relays through said contact points respectively, the contact points corresponding to the same floor being positioned adjacent each other, individual means actuatable by the operation of each of said cars connected for controlling the despaching relays corresponding to said car through said selector according as said car is or is not in use, and a plurality 50 of individual despaching visual signals at each of said floors corresponding respectively to each of said elevators and actuatable individually respectively by the closing of a corresponding despaching relay to indicate the despaching of the particular responding elevator to the calling floor.
- 50 6. In an automatic elevator despaching system for a bank comprising a plurality of elevator cars, tractive motors for said cars respectively, a single button on each floor served by said cars, a plurality of groups of despaching relays comprising one group for each floor and each group comprising one relay for each car, said despaching relays being connected for actuating said car motors, a step-by-step electrically actuatable selector comprising a plurality of engageable contact points corresponding respectively to said despaching relays and connected for successively actuating said despaching relays through said contact points respectively, the contact points corresponding to the same floor being positioned adjacent each other, individual means actuatable by the operation of each of said cars connected for controlling the despaching relays corresponding to said car through said selector according as said car is or is not in use, and a plurality 55 of individual despaching visual signals at each of said floors corresponding respectively to each of said elevators and actuatable individually respectively by the closing of a corresponding despaching relay to indicate the despaching of the particular responding elevator to the calling floor.
- 55 6. In an automatic elevator despaching system for a bank comprising a plurality of elevator cars, tractive motors for said cars respectively, a single button on each floor served by said cars, a plurality of groups of despaching relays comprising one group for each floor and each group comprising one relay for each car, said despaching relays being connected for actuating said car motors, a step-by-step electrically actuatable selector comprising a plurality of engageable contact points corresponding respectively to said despaching relays and connected for successively actuating said despaching relays through said contact points respectively, the contact points corresponding to the same floor being positioned adjacent each other, individual means actuatable by the operation of each of said cars connected for controlling the despaching relays corresponding to said car through said selector according as said car is or is not in use, and a plurality 60 of individual despaching visual signals at each of said floors corresponding respectively to each of said elevators and actuatable individually respectively by the closing of a corresponding despaching relay to indicate the despaching of the particular responding elevator to the calling floor.

HENRY LÉOPOLD ROGER ROCHE.
